UNITED STATES PATENT OFFICE.

NATHANIEL COLE, OF OTTAWA, ILLINOIS.

DESIGN FOR A DOUBLE HARNESS-LOOP.

SPECIFICATION forming part of Design No. 33,638, dated December 4, 1900.

Application filed April 5, 1900. Serial No. 11,772. Term of patent 7 years.

To all whom it may concern:

Be it known that I, NATHANIEL COLE, a citizen of the United States, residing at Ottawa, in the county of La Salle and State of Illinois, have invented and produced a new and original Design for a Double Harness-Loop; and I do hereby declare the following to be a full, clear, and exact description of the same, reference being had to the accompanying drawings, forming a part thereof.

In the said drawings, Figure 1 is a vertical longitudinal sectional view taken on the line 1 1 of Fig. 2. Fig. 2 is a plan view, and Fig. 3 is a vertical transverse sectional view, taken on the line 3 3 of Fig. 2, of a double harness-loop embodying my new design.

My design relates to the new and original shape or configuration of the article.

The leading or essential feature consists in the unitary design for a double harness-loop made the subject of illustration, comprising the shape of the open end pieces formed of the upper and lower bars A B, having convexly-rounded outer surfaces *a b* and flat horizontal inner surfaces *ef*, uniting with the solid side pieces C C, together with the central lower transverse bar D and the flat-topped

conical pin E, the said side pieces C C each having longitudinally-rounded upper surfaces extending in a single continuous concave line from end to end and the lower surface of each side piece C being formed on two concavely-rounded lines extending, respectively, from the line of one edge of the said central lower transverse bar D to the adjacent lower end bars B B.

Minor features of said design comprise the extension of the conical pin E above the plane of the longitudinal centers of the side bars C C, but terminating on the plane of the tops of the upper end bars A A.

Having thus described my invention, what I claim as new, and desire to secure by Letters Patent, is—

The design for a double harness-loop, substantially as herein shown and described.

In testimony whereof I affix my signature in presence of two witnesses.

NATHANIEL ^{his} COLE.
